BINDER

Edward John Davis, Vancouver, British Columbia,
Canada

Application April 3, 1939, Serial No. 265,820

15 Claims. (Cl. 129—16)

This invention relates to an improved binder or tray for ledger sheets, loose leaf sheets, cards, record sheets, letters, catalogues, flat samples, or similar articles.

5 An object of the present invention is the provision of a binder from which the contents may be easily and readily removed either individually or as a unit.

Another object is the provision of a binder in which the contents are securely held and yet are readily available at all times.

Another object is the provision of a binder that may be expanded or compressed from either or both ends.

15 A further object is the provision of a binder capable of being manufactured in any size and the expansion of each binder being relatively great.

A further object is the provision of a binder 20 of extremely simple construction.

A still further object is the provision of a binder which cannot go out of working order.

There are numerous binders or trays now in use but each of these of any size or capacity is 25 comparatively complicated in construction. This makes them expensive and very liable to go out of working order. Another disadvantage lies in the fact that most of them are made for a specific purpose and cannot readily be used or 30 changed for any other purpose. Furthermore, the range of expansion is extremely limited in the known binders.

A binder according to this invention is extremely simple in construction. It consists preferably of two covers pivotally mounted in independent supports with a portion of each cover projecting beyond its pivot. A back unit in the form of a tray or a plurality of posts connected together in any suitable manner is provided, 40 which unit removably rests upon the covers beyond the pivots thereof. The unit is adapted to receive the contents of the binder so that the weight of the contents actually rests upon that part of the covers beyond their pivots. This normally holds each cover in a vertical or closed position. The back unit actually is floating as the covers are so constructed that either or both of them may be pivoted outwardly into open or partially open positions without disturbing the 50 unit and the weight of the contents is adapted to hold the covers in whatever positions they are moved. It is possible to have one cover stationary and the other cover pivoted so that the latter only may be pivoted into open or partially open 55 positions. This binder not only is very simple

in construction but it may be used for many purposes while the degree of expansion is limited only by the length of the tray or posts which may be of any desired length and may be interchangeable.

5 The present invention consists of at least one cover pivotally mounted in a support with a portion of said cover projecting beyond the pivot, and a floating back unit resting on the cover beyond the pivot, said unit being formed to receive 10 the contents of the binder, as more fully described in the following specification and illustrated in the accompanying drawing, in which

Figure 1 is a fragmentary sectional view taken through a cover of the binder, said cover being 15 in closed position,

Figure 2 is a view similar to Figure 1 with the cover in open position,

Figure 3 is a fragmentary end elevation of the 20 binder partly in section,

Figure 4 is a perspective view of a connecting bar of the back unit of the binder, and

Figure 5 is a perspective view of the binder 25 with certain parts broken away for the sake of clarity.

Referring more particularly to the drawing, the binder preferably consists of a pair of covers A, pivotally mounted in supports B and a floating back unit C carried by said covers. Each support B consists of a base 10 with upwardly extending 30 arms 11 at the ends thereof. Orifices 12 are formed in the arms 11 adjacent their upper ends.

Each cover A comprises a main cover portion 13 having a reinforcing strip 13a across its inner end, and brackets 14 at the inner corners thereof. 35 Each bracket 14 is preferably in the form of a segment having a brace 15 extending outwardly therefrom to which the main cover portion 13 is secured in any suitable manner, such as by screws or rivets 16 which extend through a reinforcing plate 17 and through the portion 13 into the brace. A circular lug or pivot 18 extends outwardly from the outer surface of the bracket or segment and is situated at substantially the center point of the curve of said segment. The lugs 40 18 extend into the orifices 12 of the supports B and act as the pivots for the covers A. With this construction, the covers A are pivotally mounted adjacent their inner ends with a portion of said covers projecting beyond the pivot. A shoulder 45 20 formed on the outer surface of each segment, is adapted to limit the turning movement of the segment by abutting against the arm 11 of the base 10. A recess 21 is formed in the inner surface of that portion of the bracket projecting 50 55

beyond the pivot 18. This recess is preferably arcuate in form with its center coinciding with the center of the pivot 18. The outer edge 22 of the recess may be a continuous curve or it may 5 consist of a plurality of flat surfaces, as shown. The ends of the recess lie substantially at right angles to each other and are situated so that one end is in a vertical position when the cover is in a similar position and the other end is in a vertical position when the cover is in a horizontal position. A groove 23 is formed in the inner surface of each bracket and preferably lies in a horizontal position when the cover is in a vertical position although this is not absolutely necessary. 10 This groove extends from the recess 21 to the edge of the bracket. If desired, threaded studs 25 may be provided, said studs projecting outwardly from the lugs 18 and being adapted to receive washers 26 and wing nuts 27. 15 The back unit C preferably comprises a plurality of posts 30 having supporting means or connecting bars 31 slidably mounted thereon adjacent the ends thereof. Each post extends through an opening 32 formed in the bar 31. A 20 locking strap 33 having its central portion bent outwardly, as at 34, is held against each bar 31 by a bolt 35 which extends through the strap and is threaded into the bar. The strap is provided with a plurality of openings 36 normally regis- 25 tering with the openings 32 of the bar and through which the posts 30 extend. When the bolt 35 is tightened down, the openings 36 tend to move out of registry with the openings 32 so that the sides of the former openings press 30 against the posts to lock the bar in place. If desired, a suitable tray may be placed upon the posts 31 or a tray may be used in place of the posts. 35 When assembled, the connecting bars 31 of the back unit C extend into the recesses 21 of the portions of the covers A extending beyond the pivots. These bars merely rest upon the edges of the recesses so that the back unit is floating, that is, it will permit movement of the covers 40 without moving itself. As the bars 31 are slidably mounted upon the posts 30, either or both the covers may be moved towards or away from the center of the back unit, to adjust the effective length thereof. If desired, the supports B 45 may be mounted upon a suitable common base. Suitable punched ledger sheets, loose leaf sheets, record sheets or the like may be mounted upon the posts 30 in the usual manner. These or any other articles may be merely placed upon the 50 posts between the covers or upon a tray resting on the posts or upon a tray used in place of the posts. The covers A are normally held in a vertical or closed position by the weight of the floating back unit and the contents of the ledger 55 60 since said weight is applied to those portions of the covers extending beneath the pivots thereof. When the covers are closed, the bars are situated adjacent one end of the slots 21. 65 Each cover may be partially or fully opened merely by pivoting it outwardly to the desired extent. As the connecting bar of each cover is only resting in the recess 21, it does not interfere with the pivoting of the cover until the latter has reached substantially a horizontal position 70 75, at which time the bar abuts against the opposite end of the recess. The weight of the back unit or contents of the ledger will hold the cover in any position to which it is moved since the weight is always applied to the cover directly beneath the pivot thereof. In this way, the

weight directly below the pivot is always greater than that above the pivot so that the cover remains in the position into which it is moved. As stated above, the outer edge 22 of the recess 21 may be a continuous curve, in which case the 5 cover will remain at any desired angle, or said edge may consist of a plurality of flat surfaces so that the cover may be moved into a corresponding number of positions. When the flat surfaces are employed, the cover is held more 10 positively in any of the desired positions as it is more difficult to move the cover with the bar 31 resting on a flat surface. When there are three flat surfaces, as shown, the cover may be moved between closed, semi-open and completely open 15 positions. If desired, the wing nuts 27 may be tightened to hold the covers in any desired position. The shoulders 20 prevent the covers from moving past their horizontal positions. The contents of the binder are pressed together while 20 the covers are closed, and when either or both covers are partially or completely opened, the pressure is released so that any part or all the contents may be removed from the floating back unit. The entire back unit may be removed by 25 pivoting the covers into their horizontal positions, at which time the connecting bars 31 may be withdrawn from the recesses 21 through the grooves 23.

It is possible that only one cover A may be employed in a binder. In this case, one end of the back unit would be mounted in or upon a suitable support while the opposite end thereof would be mounted in a cover in the manner described. The posts 30 may be of any desired length and 35 each one may be a single length or it may be made in sections.

From the above it will readily be seen that a binder of extremely simple construction has been provided, in which the contents are securely held 40 and yet are readily available at all times, and from which the contents may be easily removed either individually or as a unit.

Various modifications may be made in this invention without departing from the spirit thereof or the scope of the claims, and therefore the exact forms shown are to be taken as illustrative only and not in a limiting sense, and it is desired that only such limitations shall be placed thereon as are disclosed in the prior art or are set 50 forth in the accompanying claims.

What I claim as my invention is:

1. A binder having at least one cover pivotally mounted in a support, a portion of said cover projecting below the pivot, and a floating back unit resting on the cover below the pivot, said unit being formed to receive the contents of the binder.
2. A binder having at least one cover pivotally mounted in a support, a portion of said cover projecting below the pivot, and a floating back unit removably resting on the cover below the pivot, said unit being formed to receive the contents of the binder.
3. A binder having at least one cover pivotally mounted in a support, a portion of said cover projecting below the pivot, a floating back unit resting on the cover below the pivot, said unit being formed to receive the contents of the binder, and means for adjusting the effective length of the back unit.
4. A binder comprising a pair of covers pivotally mounted in supports, a portion of each cover projecting below its pivot, and a floating back unit resting on the covers below the pivots, said 75

unit being formed to receive the contents of the binder.

5. A binder comprising a pair of covers pivotally mounted in supports, a portion of each cover 5 projecting below its pivot, and a floating back unit removably resting on the covers below the pivots, said unit being formed to receive the contents of the binder.

10. A binder comprising a pair of covers pivotally mounted in supports, a portion of each cover projecting below its pivot, a floating back unit resting on the covers below the pivots, said unit being formed to receive the contents of the binder, and means for adjusting the effective length 15 of the back unit.

15. A binder having at least one cover pivotally mounted in a support, a portion of said cover projecting below the pivot, recesses formed in the projecting portion adjacent the sides thereof, and a back unit having supporting means projecting into the recesses and resting upon the edges thereof, said unit being formed to receive the contents of the binder.

20. In a binder, the combination of at least one cover having a pair of brackets at its inner end 25 adjacent the sides thereof, said brackets being pivotally mounted in a support and each having a portion extending below the pivot, a recess in that portion of each bracket extending below the pivot, and a back unit having supporting means 30 extending into and resting on the edges of the recesses, whereby the cover is held in position by the weight of the back unit.

25. In a binder, the combination of at least one cover having a pair of brackets in the form of segments at its inner end adjacent the sides thereof, said segments being pivotally mounted at substantially the center points thereof in a support, a recess formed in each segment below 35 its pivot, and a back unit having supporting means extending into and resting on the edges of the recesses, whereby the cover is held in position by the weight of the back unit.

40. In a binder, the combination of at least one cover having a pair of brackets at its inner end adjacent the sides thereof, said brackets being pivotally mounted in a support and each having a portion extending below the pivot, an arcuate recess in that portion of each bracket extending below the pivot, the center of said recess substantially coinciding with the center point of 45 the pivot, and a back unit having supporting means extending into and resting on the edges 50

of the recesses, whereby the cover is held in position by the weight of the back unit.

5. In a binder, the combination of at least one cover having a pair of brackets in the form of segments at its inner end adjacent the sides thereof, 5 said segments being pivotally mounted at substantially the center points thereof in a support, an arcuate recess formed in each segment below its pivot, the center of said recess substantially coinciding with the center of the pivot, and a floating back unit having supporting means extending into and resting on the edges of the recesses, whereby the cover is held in position by the weight of the back unit.

10. In a binder, the combination of at least one cover pivotally mounted in a support, a portion of said cover projecting below the pivot, and a floating back unit having a plurality of posts and at least one connecting bar mounted upon said posts adapted to rest on the cover below 20 the pivot thereof.

15. In a binder, the combination of at least one cover pivotally mounted in a support, a portion of said cover projecting below the pivot, and a floating back unit having a plurality of 25 posts, at least one connecting bar slidably mounted upon said posts adapted to rest in the cover below the pivot thereof, and means for locking the bar in any desired position upon the posts.

20. In a binder, the combination of at least one cover having a pair of brackets at its inner end adjacent the sides thereof, said brackets being pivotally mounted in a support and each having a portion extending below the pivot, a recess in that portion of each bracket extending below 30 the pivot, and a back unit having a plurality of 35 posts, and at least one connecting bar mounted upon said posts adapted to extend into the recesses of the brackets, whereby the cover is held in position by the weight of the back unit.

40. In a binder, the combination of at least one cover having a pair of brackets in the form of segments at its inner end adjacent the sides thereof, said segments being pivotally mounted at substantially the center points thereof in a support, an arcuate recess formed in each segment below its pivot, and a back unit having a plurality of 45 posts, at least one connecting bar slidably mounted upon said posts adapted to extend into and rest on the edges of the recesses 50 of the segments, and means for locking the bar in any desired position upon the posts.

EDWARD JOHN DAVIS.
